UNITED STATES PATENT OFFICE.

ROBERT LEUCHSENRING, OF NEW BEDFORD, MASSACHUSETTS, ASSIGNOR
OF ONE-HALF TO FREDERICK B. NESBETT, OF SAME PLACE.

HYDRAULIC MOTOR.

SPECIFICATION forming part of Letters Patent No. 298,102, dated May 6, 1884.

Application filed November 14, 1883. (No model.)

To all whom it may concern:

Be it known that I, ROBERT LEUCHSENRING, a citizen of the United States, residing at New Bedford, in the county of Bristol and State of Massachusetts, have invented a new and useful Water-Motor, of which the following, in connection with the annexed drawings and letters of reference thereon, is a specification.

My invention consists in an impact water-wheel wherein is provided a novel adjustable and removable supplying contrivance, a novel indicator, a novel guarded air-vent, and a series of separately-constructed buckets applied upon a rabbeted hub, whereby the speed of the wheel can be regulated and indicated to an almost infinitesimal degree by hand or a speed-governor, the stream of water applied in a broad film-like sheet across the whole width of the buckets, the wheel supplied with air, and an undue accumulation of water in the outer or surrounding case of the wheel, and annoyance from such water escaping at the air-vent, and also retardation of the wheel by reason of the rotation of the exhaust water therewith prevented, while facilities for repair of the wheel proper and of the regulating contrivance are afforded.

In the accompanying drawings, Figure 1 is a vertical central section through the wheel, buckets, and adjustable supply contrivance of my invention. Fig. 2 is a vertical transverse section of the same in the line $x-x$ of Fig. 1, showing also the improved air-vent. Fig. 3 is a detail front view of the adjustable supply apparatus. Fig. 4 is a perspective top view of two contiguous buckets. Fig. 5 is a perspective bottom view of one of the buckets constructed in conformity with my invention. Fig. 6 is an elevation and sectional view showing a power-governor substituted for the hand-regulating screw of the supplying contrivance.

A represents a case; B, an impact water-wheel; C, an adjustable conduit; D, an air-supplying vent; and d, a semi-cylindrical tube applied over the said vent and extended up nearly to the highest part of the case.

The case A may be of any suitable shape, preferably in form of a scroll, as shown. In the projecting portion A' a large rectangular inlet, a, is provided, and in its divergent or

elongated curved portion A² the outlet a' is formed, while at the center of its concentric portion A bearing-hubs a² a² for a shaft, b, of the wheel B, are constructed.

The wheel proper, B, consists of a hub, b', arms b², periphery b³, provided at either side with a rabbet or step, b⁴, and a number of buckets, E. Each bucket E consists of two side portions, e, a face-plate, e', and a bottom bolting-flange, e², with a screw-hole, e³, in it. The face-plate e' and bolting-flange e² of the bucket are held upon the middle or higher portion of the periphery b³ by means of a screw, e⁴, and the side portions, e, rest upon the rabbeted edges or steps b⁴, to which they are snugly fitted. The ends e⁵ of the side portions, e, of the bucket are shaped to make a perfect fit with the face-plate e' of an adjoining bucket, and thus when all the buckets are set in place they form two continuous circular side rims for the periphery of the wheel, as well as a number of water-tight compartments of equal area, and open only at the outer periphery of the wheel proper.

An undue accumulation of exhaust-water inside of the case A and about the wheel B is prevented by the vent-hole D in the case A, and said hole, being covered by the vertical gutter-shaped air conductor or pipe d, is adapted for freely admitting air into the case, while at the same time splashing of water through the hole D and outside of the case A is avoided. The water is let into the case A and upon the wheel B by means of the adjustable conduit or inlet device C, which is constructed with a rectangular chamber, c, having a suitable head, c', (into which in practice the supply-pipe will be screwed,) and one or two flanges, c², which, by means of set-screws c³, are fastened to the outer face of the projection A', containing the opening a of the case.

Below the head c' an inclined water regulating or supply guide, c⁴, made yielding at c⁵, is fastened by means of a screw-bolt, c⁶, to one of the inner end walls of the conduit C. This guide is fitted to move water-tight between the movable plates c¹⁰ of the conduit, which plates are secured by screws c¹², and it can be readily removed from the conduit for repairs or renewal after the same has been unscrewed.

- at c^3 and taken out of the inlet a by unscrewing the plates c^{10} and turning back the bolt c^1 . A spring, F , held in place also by the bolt c^1 , bears against the guide c^4 and acts to hold or force the guide away from the inner or right-hand side of the conduit C . A set-screw, f , passed loosely through the lower portion of the outer wall of the projection A' , and screwed into the left-hand side of the conduit 5 10 C , bears against a straight surface, c^6 , of the guide c^4 , and by turning the screw f to the right the water-supply-regulating guide c^4 is caused to approach the inner or right-hand side of the conduit C , and by turning the screw in a reverse direction the guide c^4 , by force of spring F , recedes from it, thereby either diminishing or enlarging the rectangular supply-orifice c^5 of the conduit, and thus regulating in the most effective manner, and 15 20 to the nicest degree, the quantity of water for operating the wheel B , such water being supplied in a broad film-like sheet across the whole width of the buckets of the wheel. The screw f extends through the outer wall 25 30 of the inlet, opening a of the projection A' of case A , and is there provided with a flat head, f' , and pointer f^2 . A graduated dial, F' , is attached to the case A opposite the pointer f^2 , and by this means the speed of the wheel is indicated, and the operator is enabled after a little experience to at once set the screw f in the right position, in order to admit the proper or desired quantity of water into the wheel B for any required amount of power. 35 40 Instead of the screw f , worked by hand, as an adjusting and governing means, a power-governor may be employed, as shown in Fig. 6, whenever most desirable. The governor L , shown in said figure, is suitably fastened to the projection A' of case A , and its sliding stem l passes through the projection A' into the conduit C , and rests in a spindle-bearing, l' , fastened in the side c^6 of the water-regulating guide c^4 , and its collar l^2 , to which 45 50 the balls l^3 are fastened, is, by means of a pulley, l^4 , and the usual bevel-gears, revolved from the main shaft b , which is provided with a pulley, b^4 , and belt b^5 , and as the velocity of the wheel B increases this sliding stem l will be moved, and with it the guide c^4 , and thereby 55 60 is diminished the size of the supply-passage c^5 , and while the velocity of the wheel is being restored through these means to the proper or set speed the spring F acts to move the regulating-guide back to its proper or original set position.

The water-wheel herein described may be set so as to have the conduit C either vertical or horizontal, or in any other desired posi-

tion, and so also may its discharging end stand 60 either to the right or left.

The within-described conduit C , provided with the adjustable water-supply - regulating device, may be used advantageously in connection with other water-distributors and for 65 various purposes.

What I claim as my invention, and desire to secure by Letters Patent, is—

1. The combination, with the water-wheel and its inclosing case having a broad rectangular inlet, a , of the conduit C , closed on all sides, and provided with a flexible water-supply-regulating guide, c^4 , having a broad surface, and a governing means, substantially as and for the purpose described. 70

2. The combination, with the water-wheel and its inclosing-case having a broad rectangular inlet, a , of the conduit C , closed on all sides, and provided with a rectangular chamber, and a flexible water-supply-regulating guide, c^4 , 80 having a broad face, the adjusting - screw f , pointer f^2 , and dial F' , substantially as and for the purpose described.

3. The combination, with the water-wheel and its inclosing-ease, of the conduit C , closed 85 on all sides, and having the broad surfaced adjustable guide c^4 , which is made flexible at c^6 , and provided with a spring, and adapted to be fastened within the rectangular chamber of the conduit by a screw-bolt, substantially as and for the purpose described.

4. The removable conduit C , provided with a coupling-head, c' , a rectangular chamber, c , bolting-flanges c^2 , screw-plates c^{10} , and a flexible removable water-supply-regulating guide, 95 c^4 , fitted within the chamber, in combination with the projection A' , substantially as and for the purpose described.

5. The combination of the wheel B and the water-motor case A , A' , A^2 , having a suitable 100 conduit, C , and the air-supplying vent-hole D , covered by the tube d , substantially as and for the purpose described.

6. In a water-motor, the wheel B , having its periphery formed with circular rabbets b^4 , and 105 its buckets E , constructed separately with their face-plates e' and side portions, e , fitted to the rabbeted periphery, all substantially as described.

7. In a water-motor, the wheel B , having 110 separately - constructed buckets E , provided with face-plate e' , side portions, e , flanged bolt-ing portions e^2 , and end portions, e^3 , fitting the face-plate e' , substantially as described.
